CLASP

Eddie J. Bell, Ingleside, Tex.

Application January 19, 1946, Serial No. 642,277

7 Claims. (Cl. 24—261)

1

The invention relates to a clasp made of a single piece of wire bent into such shape that it has jaws which may clasp and hold any matter placed between them. They are held together or against the inserted matter by spring pressure. In one form the device may be provided with handles which may be manipulated to open the jaws. The device may be used for various purposes. It may be used to hold papers or books or to act as a clothes pin or clasp for films or prints, etc.

An embodiment of the invention is shown in the accompanying drawings in which Figure 1 is perspective of a clasp. Fig. 2 is a front elevation. Fig. 3 is a side elevation. Fig. 4 is a perspective fragmentary view of a portion of the device. Fig. 5 is a perspective view of an optional arrangement.

As shown in Figs. 1 to 4 the clasp is made from a single piece of wire which should be resilient or elastic and is bent into the proper shape. A central more or less straight bar 10 has at each end coils 11, 12. The coils 11 and 12 are oppositely wound—for instance, the coil 11 may be wound clockwise and the coil 12 counter-clockwise. Depending from the outer end of the coil 11 is a member 13 which at its bottom is turned diagonally upward into a member 14 from which is an upwardly extending member 15 which may lie substantially under the coil 12. At the upper end of the member 15 the wire may be turned inwardly to form a member 17 more or less parallel to the bar 10 and preferably stopping before it reaches the center of the bar 10. Extending upwardly from the inner end of the member 17 is a member 18 crossing the bar 10 and preferably continuing at its end into a member 19 bent to cross the bar 10 having at its end a handle or finger member 20.

Depending from the outer end of the coil 12 is a member 21 which is substantially in contact with the member 15 and which at its bottom is turned diagonally upward into a member 22 crossing the member 14. From the upper end of the member 22 is an upwardly extending member 23 which may lie substantially under the coil 11 and in substantial contact with the member 13. At the upper end of the member 23 the wire may be turned inwardly to form a member 24 more or less parallel to the bar 10 and preferably stopping before it reaches the center of the bar 10. Extending upwardly from the inner end of the member 24 is a member 25 crossing the bar 10 on the opposite side from the member 18 and

2

preferably continuing at its end into a member 26 bent to cross the bar 10 in the opposite direction from the member 19 and having at its end a handle or finger member 27.

5 The arrangement is such that when the parts are at rest, as shown in Fig. 1, the clamping members normally lie substantially in contact with each other but may be separated for receiving material to be clasped by manipulation of the handles. It will be understood that pressing together the finger pieces 20 and 27 will tend to make the lower clamping jaws made up of members 13, 14, 15 and 21, 22, 23 separate. The members 18 and 25 work on the bar 10 as a fulcrum where they cross it. The strains and direction of movement are such that this action of opening jaws tends to wind up the coils 11 and 12 and insure additional unwinding tension to close the jaws on any matter inserted to insure a certain strong hold.

If the device is to be used to attach articles to a bar, rod or rope such as a clothes line or the like, there may be provided oppositely disposed outwardly extending loops 28, 29 in the members 15 and 21 and correspondingly arranged outwardly extending oppositely disposed loops 30, 31 in the members 13 and 23 respectively. These loops make it possible to engage the rope or the like and still allow the jaws to come into close clamping contact with themselves or with interposed material.

Where the members 18 and 25 cross the bar 10 they may be provided with small offsets or loops 32 and 33 respectively and to hold them in place and restrain them from jumping or slipping out of proper adjustment there may be provided clamping or anchor members 34 shown more in detail in Fig. 4 where the I-shaped blank is shown curved and placed on the opposite side of the wire 10 from the loop 33 with the end arms 35 clamped about the member 25 both above and below the wire 10 so as to hold it in the loop 33.

40 The clamp may be made of any suitable material and the wire may be of such a character or composition that it may be used alone to securely clasp devices without injuring them. It may be desired however to prevent the wire from coming into direct contact with the devices to be clamped. To this end plastic or the like 36 may be applied to all or to the clasping portion of the device as indicated in Fig. 1 or more or less flat pieces of wood or other material 37 may be 45 held against the clasping surfaces by any suitable

ble means such as cords, wires or clasps 38 about the clasp members such as 13, 14, etc., as indicated in Figs. 2 and 3.

It is possible of course, without using the handles 20 and 21, to force the clamping members apart by any suitable means or by manual manipulation. A paper or other device to be clamped may be forced between the crossing members 14 and 22. Thus the handles 20 and 21 may be entirely omitted and if desired the members 18 and 32 may be directly connected to the bar 10. Such an arrangement is indicated in Fig. 5 where the members 18a and 32a terminate in rings or loops 40 and 41 respectively which engage the bar 10. This may be particularly desirable when the device is to be used as a paper clip to hold together two or more pieces of paper. The paper or the like may be inserted merely by sliding it between the crossing members 14 and 22 of the clamp members 13a and 21a and so into position to be fully grasped and held by the members. In this construction the loops 28, 29, 30 and 31 shown in Fig. 1 may be omitted if desired.

Various changes in construction, arrangement and relative sizes of the various elements may be made without departing from the invention.

I claim as my invention:

1. In a clasp made of a single piece of wire, a central bar, a spring coil at one end of the bar, a clamping member extending from the coil, a handle member extending from the clamping member and crossing the bar, a handle at the end of the handle member, an offset in the handle member where it crosses the bar, a second spring coil at the other end of the bar, a second clamping member extending from the second coil and normally substantially in contact with the first-mentioned clamping member, a second handle member extending from the second clamping member and crossing the bar on the side opposite to the first handle member, a second handle at the end of the handle member, the handle members after crossing the bar diverging, a second offset in the second handle member where it crosses the bar, and anchor members straddling the offsets and each on the other side of the bar from its offset.

2. In a clasp made of a single piece of wire, a central bar, a spring coil at one end of the bar, a clamping member extending from the coil, a handle member extending from the clamping member and crossing the bar, a handle at the end of the handle member, an offset in the handle member where it crosses the bar, a second spring coil at the other end of the bar, a second clamping member extending from the second coil and normally substantially in contact with the first-mentioned clamping member, a second handle member extending from the second clamping member and crossing the bar on the side opposite to the first handle member, a second handle at the end of the second handle member, the handle members after crossing the bar diverging, and a second offset in the second handle member where it crosses the bar.

3. In a clasp made of a single piece of wire, a central bar, a spring coil at one end of the bar, a clamping member extending from the coil, a handle member extending from the clamping member and crossing the bar, a handle at the end of the handle member, a second spring coil at the other end of the bar, a second clamping

member extending from the second coil and normally substantially in contact with the first-mentioned clamping member, a second handle member extending from the second clamping member and crossing the bar on the side opposite to the first handle member, and a second handle at the end of the second handle member, the handle members after crossing the bar diverging.

4. In a clasp made of a single piece of wire, a central bar, a spring coil at one end of the bar, a clamping member extending from the coil, a handle member extending from the clamping member and crossing the bar, a second spring coil at the other end of the bar, a second clamping member extending from the second coil and normally substantially in contact with the first-mentioned clamping member, and a second handle member extending from the second clamping member and crossing the bar on the side opposite to the first handle member.

5. In a clasp made of a single piece of wire, a central bar, a spring coil at one end of the bar, a clamping member extending from the coil, a handle member extending from the clamping member and crossing the bar, an offset in the handle member where it crosses the bar, a second spring coil at the other end of the bar, a second clamping member extending from the second coil and normally substantially in contact with the first-mentioned clamping member, a second handle member extending from the second clamping member and crossing the bar on the side opposite to the first handle member, and a second offset in the second handle member where it crosses the bar.

6. In a clasp made from a single piece of wire, a central bar, a spring coil at one end of the bar, a clamping member extending from the coil, a loop extending from the clamping member and engaging the bar, a second spring coil at the other end of the bar, a second clamping member extending from the second coil and normally substantially in contact with the first mentioned clamping member, and a second loop extending from the second clamping member and engaging the bar on the side opposite to the first mentioned loop.

7. In a clamp made from a single piece of wire, a central bar, a spring coil at one end of the bar, a clamping member extending from the coil, means for loosely connecting the member to the bar, a second spring coil at the other end of the bar, a second clamping member extending from the second coil and normally substantially in contact with the first mentioned clamping, and means for loosely connecting the second clamping member to the bar on the side opposite to the first mentioned connecting member.
